COMBINED COVER AND SPEAKER ENCLOSURE
FOR PHONOGRAPHS OR THE LIKE

George M. Buckler, Baldwinsville, N.Y., assignor to General Electric Company, a corporation of New York

Filed Jan. 7, 1966, Ser. No. 519

Term of patent 14 years

(Cl. D56—4)

FIGURE 1 is a perspective view of a combined cover and speaker enclosure for phonographs, showing my new design;

FIGURE 2 is a front elevational view of the design;

FIGURE 3 is a top plan view of the design, rotated 180 degrees from the view shown in FIGURE 2;

FIGURE 4 is a rear elevation view of the design;

FIGURE 5 is an end elevation view of the design, the opposite end being a mirror image of the end shown; and

FIGURE 6 is a bottom plan view of the design.

The dominant features of my design reside in the portions shown in full lines.

I claim:

The ornamental design for a combined cover and speaker enclosure for phonographs or the like, substantially as shown and described.
